UNITED STATES PATENT OFFICE

2,570,594

DISPLAY CARD EXHIBITING DEVICE FOR
TELEVISION BROADCASTING

Ronald J. Rockwell, Cincinnati, Ohio, assignor to
Crosley Broadcasting Corporation, Cincinnati,
Ohio, a corporation of Ohio

Application October 28, 1950, Serial No. 192,746

3 Claims. (Cl. 40—63)

1

The present invention relates to a novel device for presenting a sequence of display cards to be televised. The invention is herein variously referred to as a "card dropper" or "card exhibiting device."

Black and white or monochrome television has now met with widespread public acceptance, and the national viewing audience is thoroughly familiar with the business cards and similar "still picture" display material appearing on receiver screens, generally in the intervals between programs. Occasionally several of these display cards are televised in sequence, and the transmitted images accordingly appear in sequence on the receiver screens. At other times only one card is displayed between programs. It has been found desirable to provide a suitable exhibiting device for controlling the sequence in which such cards are displayed. The general object of the invention is to satisfy this requirement.

For a better understanding of the invention, together with other and further objects, advantages, and capabilities thereof, reference is made to the following description of the accompanying drawings, in which there is illustrated a card exhibiting device in accordance with a preferred form of the invention.

In the drawings:

Fig. 1 is a side view of my novel card presenting device;

Fig. 2 is a rear view of the device;

Fig. 3 is a fragmentary plan view showing the step-by-step mechanism incorporated in the device as seen by an observer looking down from a position above the device; and

Fig. 4 is a fragmentary sectional view of the main vertical support member and cam-supporting bracket as taken along the section line 4—4 of Fig. 2, looking in the direction of the arrows.

Referring now specifically to Fig. 1 of the drawings, the reference numerals 10, 11, 12, and 13a designate advertising cards or the like, each generally rectangular in conformation and thin in section, and each having advertising or display material on the front side thereof, the front side of card 13a, for example, being designated by the reference numeral 14. It will be understood that the material on the front side of the card presented for view is televised by being exposed to a conventional television camera (not shown) either directly or through a suitable optical system. The operation of the device is such that

2

when the exhibition of card 13a has been completed, the card is "dropped" or rotated through an angle of 90 degrees (counter-clockwise, Fig. 1), so that it is placed out of viewing position. 5 The dashed outline 13b is indicative of an instantaneous position assumed by card 13a, for example, when it is dropping out of viewing position. When card 13a is dropped out of viewing position the device functions to place card 12 in the position formerly occupied by card 13a, and the sequence of exhibition of card 12 and dropping of card 12 is repeated, whereupon card 11 is automatically placed into the position theretofore occupied by card 12, and so on.

10 15 15 The over-all gross operation of the device having been set forth, the description now proceeds to the mechanical details thereof.

The device comprises the following main components: First, a suitable metallic base 16, preferably generally box-like in shape; second, a main vertical support member 17, suitably secured to the base and extending upwardly therefrom; third, a pair of reinforcing struts 18 and 19 for maintaining support 17 in an upright position; fourth, a worm gear 20 which meshes with the top edges of the cards to position, advance, and finally release them; fifth, a ratchet or step-by-step mechanism 21, each action of which turns the worm gear through 360 degrees (counter-clockwise as viewed from the rear, the threading of the worm gear being right-handed); sixth, a solenoid 22 and lever arm 23 for actuating the ratchet mechanism; seventh, a push button switch 24 having contacts in the supply circuit of the solenoid for periodically energizing the solenoid; eighth, a follower member 27, having substantially the same configuration as the cards, suitably biased to advance the cards step by step as the worm gear turns.

45 In order successively to present the cards 13a, 12, 11, and 10 for televising, the only manual operation that must be performed by the operator is the depression of the push button on switch 24, which operation closes the electric supply circuit to the winding of solenoid 22. When the supply circuit is closed armature 29 is drawn downwardly and held in that position until the switch push button is released. A lever 23 is pivotally mounted at 28 on a suitable supporting bracket 66 secured to vertical support 17, and the lever 23 is mechanically connected to the armature 29 of solenoid 22 by a link 67, so that the energizing of the solenoid and the resulting

depression of armature 29 cause lever 23 to swing counter-clockwise as seen from the rear (Fig. 2).

The step-by-step mechanism comprises a shaft 30, journaled in bearings provided in a U-shaped bracket 31, which bracket is mounted on and rigidly secured at 50 (Fig. 4) to a shaft 32, journaled in bearings provided in a U-shaped bracket 33. Bracket 33 is mounted on and rigidly secured to the vertical support member 17. Worm gear 20 is mounted on and rigidly secured to shaft 30. The unit comprising gear 20, shaft 30, bracket 31, and shaft 32 is made rotatable, so that gear 20 and shaft 30 may be lifted upwardly (arrow A, Fig. 1) to permit loading (replacement) or unloading (withdrawal) of the cards 13a, 12, 11, and 10. A tension spring 34 draws an upwardly extending crank 35 on shaft 32 toward support 17 and biases the unit (including elements 20, 30) counter-clockwise (Fig. 1), shaft 30 normally abutting against a limit stop 36 secured to vertical support 17. When gear 20 is manually lifted upwardly (arrow A, Fig. 1), crank 35 turns clockwise against the tension of spring 34.

The step-by-step mechanism comprises a spring-retumed pulley 38, concentric with and freely mounted for rotation on shaft 30. A string 39 is secured at one end to the pulley at 51, wound about the reduced portion of the pulley and secured at its other end to lever 23 in such a manner that the pulley is turned 370 degrees counter-clockwise (reference point is at rear) when lever 23 is depressed by solenoid 22. When the solenoid is de-energized, the pulley 38 is returned 370 degrees clockwise to its original position by a coil spring 41 concentrically disposed on shaft 30, said spring having one end secured to bracket 31 and the other end secured to pulley 38 at 42. The return of the pulley "winds up" string 39 sufficiently to swing lever 23 (clockwise, Fig. 2) to its original position. String 39 passes through aperture 59 in bracket 31.

Projecting from the front side of pulley 38 is a pawl 43, the function of which is to actuate a ratchet wheel 44. These parts are illustrated in Fig. 3 in the relative positions they assume before depression of lever 23. When the lever is depressed, pawl 43 turns counter-clockwise (Fig. 2) about 10 degrees, then engages the shoulder 45 of the "drop" of ratchet wheel 44, then forces the ratchet 44 to rotate counter-clockwise through 360 degrees, the pulley and ratchet rotating in unison during this phase of operation. The ratchet is then held in position by a stop 46, whereupon the pulley 38 and pawl 43 are spring-retumed, rotating clockwise 370 degrees relative to the pulley, the tip of pawl 43 following the rising rear surface 47 of ratchet wheel 44, until the pawl tip snaps past the shoulder 45 and finally assumes the position illustrated in Fig. 3.

While the ratchet wheel is being turned counter-clockwise (as arm 23 is depressed), its rising surface 49 pushes forwardly (Figs. 2 and 3) a spring-biased stop 46, which finally snaps past the shoulder 50 at the end of the actuation of the ratchet to hold the ratchet in position. The ratchet position is maintained, as stated above, while the pulley 38 is spring-retumed and the arm 23 is elevated. Accordingly, ratchet wheel 44 is generally circular in shape. Formed on each side of the ratchet is a cam surface gradually rising in a clockwise direction (Fig. 2)

and terminating in a drop (45 or 50). The ratchet wheel is rigidly concentrically mounted on shaft 30.

Stop 46 projects from an upwardly extending cantilever-type spring 65, mounted on the front of bracket 31, and the stop 46 extends through an aperture in the upstanding front leg of bracket 31.

Follower member 27 (Fig. 1) is urged forwardly by a plunger member 54, the front end of which is rigidly secured to the follower member at 63. Plunger 54 slidably projects through support member 17 and a bearing 55 rigidly secured to member 17. A coiled spring 56 has one end secured to bearing 55 at 57 and the other end secured to the rear of the plunger at 58 to urge the plunger and follower member 27 forwardly at all times so that when a card such as 13a is disengaged from the threads of worm gear 20 the card is dropped in a counter-clockwise direction (Fig. 1) out of viewing position, the turning moment of the card being about its end 60, support 16 being provided with a projection or flanged at 61 (Fig. 1) to permit gravitational forces to turn the card in that manner.

It will be understood that the plug 62 is inserted in a household power supply outlet in conventional manner, and that the push button on switch 24 is depressed to close the energizing circuit for the solenoid when the exhibition of card 12, for example, is desired.

Having fully described my invention, I claim:

1. A device for presenting a sequence of display cards to be televised, comprising a base member providing a support for the lower edges of said cards, a projection on the base member for securing the lower margin of the displayed one of said cards, follower means for yieldably urging said cards toward the display position, a worm gear having threads in engagement with the top edges of said cards to control the position of said cards, means for rotatably mounting said worm gear relative to said support, and electrically controlled step-by-step actuating means for rotating said worm gear to disengage one card at each step from the threads of said worm gear to permit said follower member and projection cooperatively to drop the last-displayed card from viewing position.

2. A device for presenting a sequence of display cards to be televised, comprising a base member providing a support for the lower edges of said cards, a projection on the base member for securing the lower margin of the displayed one of said cards, follower means for yieldably urging said cards toward the display position, a worm gear having threads in engagement with the top edges of said cards to control the position of said cards, means including a shaft extending in a direction perpendicular to said cards and a bearing bracket for axially rotatably mounting said worm gear relative to said support, means for swingably mounting said shaft and bearing bracket about an axis parallel to said cards to permit disengagement of said gear from said cards, a spring for normally urging said shaft and bearing bracket into such a position that said worm gear engages said top edges, and electrically controlled step-by-step actuating means for rotating said worm gear to disengage one card at each step from the threads of said worm gear to permit said follower member and projection cooperatively to drop the last-displayed card from viewing position.

3. A device for presenting a sequence of display

cards to be televised, comprising a base member providing a support for the lower edges of said cards, a projection on the base member for securing the lower margin of the displayed one of said cards, follower means for yieldably urging said cards toward the display position, a worm gear having threads in engagement with the top edges of said cards to control the position of said cards, means for rotatably mounting said worm gear relative to said support, step-by-step actuating means for rotating said worm gear to disengage one card at each step from the threads of said worm gear to permit said follower member and projection cooperatively to drop the last-displayed card from viewing position, a solenoid for controlling said actuating means, and a manually operable electrical switch in circuit with said solenoid.
